UNITED STATES PATENT OFFICE

115,699

DESIGN FOR A SPACE HEATER

Aloysius W. Becker, Chicago, Ill., assignor to
Dearborn Stove Company, Chicago, Ill., a cor-
poration of Illinois

Application February 23, 1939, Serial No. 83,153

Term of patent 3½ years

To all whom it may concern:

Be it known that I, Aloysius W. Becker, a citizen of the United States and resident of Chicago, in the county of Cook and State of Illinois, have invented a new, original, and ornamental Design for a Space Heater, of which the following is a specification, reference being had to the accompanying drawing, forming a part thereof;

Fig. 1 is a perspective of the space heater, showing my new design.

Fig. 2 is a side elevational view of said space heater.

Fig. 3 is a top plan view of said space heater.

The dominant features of my design are shown in solid black lines.

I claim:

The ornamental design for a space heater, as shown and described.

ALOYSIUS W. BECKER.
